INVENTOR

Charles W. McCutchen,

By B. F. James, Attorney

UNITED STATES PATENT OFFICE

CHARLES W. McCUTCHEON, OF PEEKSKILL, NEW YORK.

MEANS FOR ATTACHING STOVE-LEGS.

SPECIFICATION forming part of Letters Patent No. 267,911, dated November 21, 1882.

Application filed June 12, 1882. (Model.)

To all whom it may concern:

Be it known that I, CHARLES W. McCUTCHEON, of the city of Peekskill, in the county of Westchester and State of New York, have invented certain new and useful Improvements in the Manufacture of Stoves; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

My invention relates to improvements in the manufacture of stoves, and the object is to construct a new means for attaching the legs to the bottom of a stove, so that they can be more readily and easily attached and detached, when desired, and that they will not become detached when once placed in position on the stove.

The invention consists in forming in the stove-bottom, where the legs are to be secured, a peculiar-shaped hole of slightly-elliptical form, into which a shank or pintle on the stove-legs, having a beveled head, fits, and they are held in place by a curved or cam-like projection formed on the bottom of the stove, with which a projection on one side of the shank comes in contact when the two are brought together in their relative positions on the stove, all of which will be more fully described hereinafter, reference being had to the accompanying drawings and the letters of reference marked thereon.

Like letters of reference refer to like parts in the different figures of the drawings, in which—

Figure 1 is a rear view of the stove-leg secured in position on the stove-bottom. Fig. 2 is a vertical cross-section of the same on line $\alpha\alpha$. Fig. 3 is an under side view of part of the bottom. Fig. 4 is a top view of the stove-leg.

In the drawings, A represents part of the bottom of a stove, in which is cast a hole, B, which is of slightly-elliptical form, and having its edges beveled, so as to fit around the beveled edges b of a shank or pintle, C, on the stove-leg F. In the rear of the hole B is ar-

ranged a curved or cam-like projection, D, with which a projection, E, on the rear side of the shank comes in contact when the two are brought together. By means of these two projections, as well as the beveled head of the shank and the beveled edges of the hole, the leg is firmly secured in its position on the bottom of the stove. On each side of the leg is formed a lug, $e e$, against which the flange f of the stove-bottom bears, and the leg is thereby prevented from turning when secured in place. The beveled sides of the shank rest on the beveled sides of the hole, as shown in Fig. 1.

The operation is as follows: When the leg is to be applied to the bottom of the stove it is first entered, with the shank, at about a quarter-turn from its proper position, into the elliptical hole, and then by revolving it the lug E and projection D come in contact with each other, and when they arrive at the highest point of the projection D and the lowest part of the lug E, or in axial line, they will clamp the bottom of the stove and the leg firmly together, and by the lugs $e e$ on each side of the leg it is prevented from revolving too far, and is held in place until loosened by the hands. The beveled ends of the elliptical hole permit the easy entrance of the shank, while the beveled sides, which are in reverse direction to the ends, hold the edges of the shank.

What I claim as my invention, and desire to secure by Letters Patent, is—

1. The leg F, having formed upon it the shank provided with lug E, beveled head-piece b , and projections $e e$, in the manner and for the purpose herein shown and described.

2. The combination of a stove-bottom, A, having holes B, whose sides and ends are beveled in opposite directions, with legs F, having shank C, with beveled head b , as shown, and for the purpose specified.

3. The combination of a stove-leg, F, having shank C, provided with lug E and beveled head, with the stove-bottom A, having elliptical holes B, with sides and ends beveled in reverse directions, and the curved projection D, all arranged substantially as shown, and for the purpose set forth.

4. The combination of a stove-leg, F, hav-

ing shank C, provided with lug E, beveled head b, and lugs e e, with the stove-bottom A, having elliptical holes B, with sides and ends beveled in reverse directions, and the curved 5 projection D, all constructed and arranged as shown, and for the purpose herein specified.

In testimony that I claim the foregoing as

my own invention I affix my signature in presence of two witnesses.

CHARLES W. McCUTCHEON.
